UNITED STATES PATENT OFFICE.

JOHN W. BUCHANAN, OF BOSTON, MASSACHUSETTS, ASSIGNOR OF ONE-HALF TO
GEORGE E. SANFORD, OF BOSTON, MASSACHUSETTS.

TYPEWRITER.

1,389,120.

Specification of Letters Patent. Patented Aug. 30, 1921.

Application filed July 16, 1919. Serial No. 311,282.

To all whom it may concern:

Be it known that I, JOHN W. BUCHANAN, a citizen of the United States, residing at Boston, in the county of Suffolk and State 5 of Massachusetts, have invented certain new and useful Improvements in Typewriters, of which the following is a specification.

The invention has for an object to provide a typewriter adapted to be taken down 10 or folded and carried in the pocket. It is also an aim to give an improved type bar mechanism suitable for use in a typewriter wherein a traveling basket of type is employed. A further aim is to effect improvements 15 in the manner of assembling and connecting the parts in a typewriter of this character.

Additional objects, advantages and features of invention will appear from the construction, arrangement and combination of parts hereinafter set forth and shown in 20 the drawings, wherein,

Fig. 1 is a top plan view of one embodiment of my invention,

Fig. 2 is a cross section on the line 2—2 of Fig. 1,

Fig. 3 is a longitudinal sectional view on the line 3—3 of Fig. 1,

Fig. 4 is a fragmentary horizontal sectional view on the line 4—4 of Fig. 2,

Fig. 5 is a fragmentary sectional view on the line 5—5 of Fig. 3,

Fig. 6 is a detail elevation of one of the type bar units,

Fig. 7 is a similar view of the unit in retracted position,

Fig. 8 is a detail of the paper feed,

Fig. 9 is a detail of the spacer and carriage feeding device.

There is illustrated a typewriter comprising two U-shaped head blocks 10 having flat bases intended to form the ends of the frame on the typewriter, each of these blocks having at opposite upstanding ends near the top 40 suitable mortises 11, of peculiar shape, into which the ends 12 of rails 13 may be engaged, to interlock with the blocks, the formation of the mortises being such that the rails may be pressed thereinto from the direction of the ends of the blocks. The rails 45

13 are formed in three sections, the middle section being dove-tailed into the end sections, the mortise running in horizontal direction and pins 14 may be employed to se-

cure the joints further. The rails 13 are 55 ordinarily of such a length when assembled that they will hold the blocks apart a distance sufficient to receive a letter sized sheet laid cross-wise of the rails 13. A platen plate 15 is provided, set in suitable 60 sockets intermediately between the rails 13, and at a lower level. Each of the blocks is also provided with a suitable centrally located bracket 16, in which a ribbon roller 17 is mounted, a ribbon 18 being provided, 65 wound from one to the other in any suitable manner. Mounted between the blocks 10 beneath one of the rails 13, there is a large paper feed roller 19, over which there is a second feed roller 20 in contact with the 70 first, while above the small roller there is mounted a shaft 21 also revoluble in the head blocks 10, and having a worm 22 thereon adjacent one end of a sufficient extent for the purpose to be described. The last named 75 shaft and rollers are preferably in section, joined at the places indicated by vertical lines thereon in Fig. 3. Upon the shaft 21 and the shaft of the roller 20 there are secured gears 23 and 24 respectively, the gear 80 23 having in the present instance but one tooth, as illustrated, and the teeth on the gear 24 being so spaced that the teeth thereof will be engaged successively by the tooth of the gear 23 as it rotates. Upon the shaft 85 25 of the large roller 19 there is a large gear 25, loosely revoluble and carrying a spring pressed pawl 26 engaging a ratchet 27 fixed upon the shaft of the roller 19 in any suitable manner. The pawl and ratchet device 90 is intended to operate to move the feed roll only upon return movement of the traveling member hereinafter described. Longitudinally reciprocable upon the rails 13, there is mounted in a suitable manner a traveling 95 member 28, having upon its upper side a circular dial 29 and having thereunder a circular casing 30, resembling in form an inverted cheese box, stopping short of the platen plate 15 and having a type basket 31 100 in its lower part. Mounted for vertical reciprocation and rotation in the upper part of the casing 15 there is an operating knob 32, having a stem portion 33 rectangular at its upper part extended downwardly and 105 provided with a laterally projected arm 34 serving as a striker, at its outer end being suitably shaped to engage respective operat-

ing rods of type action to be described. Upon the top of the casing there is mounted a suitable spring 35 bearing upon the lower end of the stem 33 to hold it normally at the 5 upper limit of its movement. A pointer 36 is provided, having its base snugly engaged upon the rectangular portion of the stem 33, a small spring 37 being confined between the upper side of the pointer and the knob 32. 10 The stem 33 is hollow, and mounted for vertical reciprocation therein there is a small rod 40, headed at its upper end for engagement by the forefinger of an operator, or by the palm, as required, a slot being formed in 15 the side of the stem 33 within the casing 30, and having a flange 41 secured to the stem 40 therethrough, the flange being of annular form and encircling the lower part of the stem 33. Mounted upon the under side of 20 the top of the casing, there is a bell crank 42 having one arm resting upon the flange 41 the other extending downwardly and being connected by a link to a bell crank 44 mounted for oscillation in a horizontal plane, one 25 arm being projected outwardly into close proximity with the rail 13 at one side, the parts being located so that this outwardly projecting arm will move rearwardly when the rod 40 is depressed, having regard to the 30 direction in which it is desired that the traveling member shall move during the typewriting of a line. The outer end of the arm 44 is provided with a suitable dog 45 to engage the rack face 46 formed upon the 35 adjacent rail 13, a spring 47 being engaged with the crank 44 to return it to initial position when the rod 40 is relieved of pressure. If desired, the cranks 42—44, the link, dog and spring may be duplicated at the opposite 40 site of the traveling member, and a rack face formed upon the inner side of each rail 13, so that a forward impulse will be exerted upon the traveling member at each side. The upper end of the rod 40 is projected a 45 sufficient distance above the knob 32 to permit independent operation of the rod and propelling devices without movement of the knob 32, so that spacing between words may be attained.

50 The top of the casing 30 is provided with a concentric series of guide lugs 50 arranged to receive the outer end of the striker arm 34 therebetween, to engage the upper ends of operating rods 51, which are extended slidably upward through the top of the basket 31 for a short distance, but stopping short of the upper side of the blocks 50. Each rod 51 is connected with a respective type bar mechanism constructed as follows:

55 A mounting plate 52 is provided for the type bar mechanism, including a base flange 53 riveted or otherwise secured to the cylindrical wall of the basket 31, the body of the plate extending at right angles to the flange 60 or in a plane parallel to a diametrical plane

of the basket. The mounting plate includes two fulcrum arms 54 and 55, one closely adjacent the top of the basket, while the other lies on a level closely adjacent the bottom of the basket. Upon the arm 54 there is pivoted a guide bar 56, stamped from sheet metal and of rectilinear form from closely adjacent its pivot to its outer part. Upon this bar there is slidably a sleeve element 57 of a type bar 58, snugly fitted upon the bar 56 for sliding movement, and having a lateral ear 59 connected to a bell crank or link 60, pivoted upon the lower arm 55 of the plate 52, the outer end of the crank moving in a radius stopping short of the pivot of the 70 guide bar upon the arm 54. A suitable spring 61 is connected to the crank 60 and to the central part of the plate 52 between the arms thereof to hold the type mechanism normally in initial retracted position, as shown 75 in Fig. 7 where the outer end of the crank 60 falls just below the base pivot of the bar 56, and slightly outward thereof with respect to the center of the type basket. The ear 59 upon the type bar is of such length as 80 to permit the latter to lie closely against the crank 60 when the parts are retracted, the type 62 upon the outer end of the bar being then held closely adjacent the base pivot of the crank 60. The lower end of the operating 85 rod 51 is connected to the crank 60 in the direction of the center of the basket from the base pivot of the crank and slightly thereabove, when the parts are in retracted position, as shown in Fig. 7. The rod is also 90 curved at its lower end so that the parts connected to the link 60 may swing outwardly a distance beneath the arm 55 when the rod 51 is forced to the lower limit of its movement, without interference in the operation 95 of the crank 60. In other words, the body of the rod 51 is offset toward the center of the basket from its point of connection with the link 60. With the parts in initial position as shown in Fig. 7, downward pressure 100 upon the upper end of the operating rod 51 will cause the link to bear upon the type bar sleeve swinging the bar rapidly inward upon the pivot of the guide bar while the sleeve 57 moves outwardly upon the bar, the initial 105 movement of the extremity of the bar being inwardly and upwardly while its final movement is abruptly downward until its strikes upon the platen bar 15, or material superposed thereon. The type face 62 at the inner 110 end of the type bar should of course be arranged in a plane diagonal to the medial line of the type bar so that it will lie approximately in a horizontal plane when the parts are extended, the extended position being 115 shown in Fig. 6. The length of the type bars is also such that they will all strike approximately upon the vertical axis of the type basket.

While I have illustrated the knob and other 120

parts between the knob and the type bar mechanism as the best means which I have thus far designed for operating the type bar mechanism, it will be understood that various other means may be employed as found desirable for operating the type bar mechanism, and various carriage moving mechanisms may also be employed for effecting movement of the traveling member upon the 10 supporting rails.

The worm on the shaft 21 is engaged by a stud arm 22', mounted on the side of the casing 30 and projecting into close relation with the shaft, as shown in Fig. 2. This 15 causes rotation of the shaft to correspond to the number of convolutions of the worm upon the shaft, thereby rotating the gears 24 and 25. Rotation of these gears in one direction causes the paper feed rolls 19 and 20 to be rotated through the agency of the pawl 26, while reverse movement is idle, owing to the non-engagement of the pawl.

The casing 30 has a stud 22' projected therefrom radially into close proximity with the shaft 21, whereby upon reciprocation of the traveling element the shaft 21 will be correspondingly rotated, actuating the ratchet device 26, by which the rollers 19 and 20 are rotated to feed the paper, indicated at A in Fig. 2.

What is claimed:

1. A typewriter comprising an elongated platen bar, parallel guide rails, a traveling type basket carried thereby, a plurality of 35 type printing units mounted in the basket each including an upwardly disposed operating member adapted to be depressed to operate its respective type printing element,

said type printing elements being each adapted to print a character centrally beneath the 40 basket with a downward stroke, an operating knob centrally mounted with respect to the type printing element and revoluble in the basket having an arm movable to selectively engage alternatively the operating 45 members of the type printing units, and being vertically reciprocable for operation; and means associated therewith to move the basket longitudinally upon each vertical reciprocation of the operating knob. 50

2. In a typewriter, a circularly arranged series of type mechanisms each including upwardly projected operating stems and resilient means to hold the stems at the upper limit of their movement, a central revoluble 55 and vertically reciprocable striker, resilient means to hold the striker at the upper limit of its movement, said striker including an arm movable into registry selectively with the operating rods of the type mechanism, 60 for the purposes described.

3. In a typewriter including a frame and traveling member, a type and spacer mechanism including a vertically reciprocable spacer key having a large knob and a type 65 operating mechanism including a reciprocable member concentrically located in said knob and exposed outwardly of the one first mentioned.

In testimony whereof I have affixed my 70 signature in presence of two witnesses.

JOHN W. BUCHANAN.
